UNITED STATES PATENT OFFICE.

FREDERICK HACHMANN, OF ST. LOUIS, MISSOURI, ASSIGNOR OF ONE-HALF TO DAVID M. HUTCHINSON, OF FERGUSON, MISSOURI.

HOSE-MENDER.

1,329,121.

Specification of Letters Patent. Patented Jan. 27, 1920.

Application filed January 20, 1919. Serial No. 271,979.

To all whom it may concern:

Be it known that I, FREDERICK HACHMANN, a citizen of the United States, and resident of the city of St. Louis and State 5 of Missouri, have invented certain new and useful Improvements in Hose-Menders, of which the following is a specification containing a full, clear, and exact description, references being had to accompanying 10 drawings, forming a part thereof.

My invention relates to certain new and useful improvements in hose menders and has for its primary object the construction 15 of a mender of two parts, the same being united together and capable of being applied to a hose and mending the same without the operation of any special tools, and further a mender which can be cheaply manufactured and easily applied to the hose 20 and if desired, removed therefrom.

In the drawings:

Figure 1 is side elevation, showing my device as applied to a hose.

Fig. 2 is a longitudinal section of the 25 same.

Fig. 3 is a side view of my improved mender before being applied to the hose.

Fig. 4 is an end view of my invention before being applied.

Fig. 5 is an enlarged fragmental section 30 showing the method of securing the shell and coupling sleeve together.

Referring to the drawings, 6 indicates the two sections which are to be connected in the 35 operation of mending the hose. The mender comprises a coupling sleeve 7 which is provided on each end with shoulders 8 and intermediate said shoulders is an integral rib 9, said rib being provided with a peripheral 40 groove 10.

11 indicates a cylindrical shell in which the rib 9 of the coupling sleeve 7 is adapted to snugly fit. This cylindrical shell is made 45 out of sheet metal and is secured to the rib 9 by being upset at certain points throughout its circumference as at 12 by means of a center punch or any other suitable instrument.

By means of forcing the shell inward as 50 at 12, a portion of the metal of the shell is forced into or seated in the groove 10 which firmly unites the shell 11 to the rib 9. One end of the shell 11 is provided with a series

of rectangular slots 13 and the opposite end is provided with a series of slots 14. These 55 slots, as it were, are staggered or offset relative to each other. By the formation of the slots 13, a series of tongues 15 are formed and by the formation of the slots 14, a series of tongues 16 are formed, which are 60 likewise staggered or offset relative to each other,—that is to say, the slots 13 are centrally opposite the tongues 16 and the slots 14 are centrally opposite the tongues 15. The ends of the tongues 15 and 16, when 65 bent downwardly to clamp the hose members 6, lie in a plane struck through the front parts of the shoulders 8, as illustrated in Fig. 2. Before the mender is applied, these tongues are slightly forced outwardly 70 as illustrated in Fig. 3, so as to permit the insertion of the hose sections.

In the operation of mending or connecting a hose, the ends of the coupling sleeve 7 are inserted into the ends of the hose sections 75 and then the tongues 15 and 16 are bent downwardly by any suitable instrument until they firmly engage the exterior surfaces of the hose sections as illustrated in Fig. 2.

The coupling sleeve 7 is preferably cast and as previously stated, the shell 11 is formed of sheet metal. The rib 9 not only answers as a means to firmly secure the shell 11 to the mender, but also acts as an abut- 85 ment for the ends of the hose sections as illustrated in Fig. 2.

It will be observed that the rear surfaces of the shoulders 8 are rather abrupt so that when the tongues 15 and 16 are bent downwardly, the hose sections 6 are given a rather abrupt bend as at 17.

A mender constructed according to my improved device is cheaply manufactured and cheap to install and firmly unites the 95 hose sections. If it is desired to remove the mender, this may be accomplished by inserting an instrument in the slots 13 and 14 and bending up the prongs so that they are disengaged from the hose sections.

My improved mender is adapted to mend hose of different ply or thicknesses. It is made for the heaviest hose and by bending down the prongs, it may be adjusted to a thinner hose. It will be observed that, when 105 it is applied to a hose, it projects slightly

beyond the exterior surface of the hose and does not form an appreciable obstruction on the hose.

Having fully described my invention,
5 what I claim is:

A hose mender comprising a coupling sleeve provided on each end with a shoulder and intermediate the end shoulders with an integral rib provided with a peripheral 10 groove, a shell provided on each end with

tongues mounted on said rib and secured thereto by forcing a portion of the metal into said groove.

In testimony whereof, I have signed my name to this specification, in presence of two 15 subscribing witnesses.

FREDERICK HACHMANN.
